(57) **CLAIM**

The ornamental design for a disinfection device as shown and described.

DESCRIPTION

FIG. 1 is a perspective view of a disinfection device in a non-illuminated state showing our new design.

FIG. 2 is a front view of the disinfection device of FIG. 1.

FIG. 3 is a rear view of the disinfection device of FIG. 1.

FIG. 4 is a top view of the disinfection device of FIG. 1.

FIG. 5 is a bottom view of the disinfection device of FIG. 1.

FIG. 6 is an enlarged left-side view of the disinfection device of FIG. 1.

FIG. 7 is an enlarged right-side view of the disinfection device of FIG. 1.

FIG. 8 is a perspective view of the disinfection device of FIG. 1 in an illuminated state.

FIG. 9 is a front view of the disinfection device of FIG. 8.

FIG. 10 is a rear view of the disinfection device of FIG. 8.

FIG. 11 is a top view of the disinfection device of FIG. 8.

FIG. 12 is a bottom view of the disinfection device of FIG. 8.

FIG. 13 is an enlarged left-side view of the disinfection device of FIG. 8; and,

FIG. 14 is an enlarged right-side view of the disinfection device of FIG. 8.

The disinfection device is shown with symbolic breaks, defined by breakaway lines. The appearance of any portion

(Continued)

of the article between the breakaway lines forms no part of the claimed design. The breakaway lines also form no part of the claim.

The evenly spaced broken lines shown in the drawings depict portions of the disinfection device that form no part of the claimed design. The dash-dash-dot and dot-dot-dash broken lines show different illumination patterns and form no part of the claimed design. All broken lines form no part of the claimed design.

1 Claim, 8 Drawing Sheets
